UNITED STATES PATENT OFFICE.

JAMES C. ANDERSON, OF HIGHLAND PARK, ILLINOIS.

PROCESS OF REDUCING CLAY, CLAY-SHALE, &c.

SPECIFICATION forming part of Letters Patent No. 248,080, dated October 11, 1881.

Application filed July 23, 1881. (No model.)

To all whom it may concern:

Be it known that I, JAMES C. ANDERSON, a citizen of the United States, and a resident of Highland Park, in the county of Lake and State of Illinois, have invented a new and useful Process of Reducing Clay, Clay-Shale, Feldspathic, Granitic, and other analogous substances to a powdered or pulverized condition, of which the following is a specification.

The object of my invention is to reduce to a powdered or pulverized condition clay, clay-shale, feldspathic and granitic rocks, or other analogous materials while in a dry, or practically-dry, condition; and my invention consists in passing the clay, clay-shale, feldspathic and granitic rocks, or other analogous materials through a mechanism by its own gravity, and subjecting said material while in its passage through said mechanism to the action of armed cylinders rotated at a high speed, which creates opposing currents in the said material of great velocity, and which causes the different currents to collide and more thoroughly disintegrate the particles.

The mechanism which I prefer to use forms the subject-matter of a separate application filed by me June 16, 1881, serial No. 35,839; but other mechanism producing the same results, in substantially the same manner, will be considered within the scope of my invention.

It is desirable in the reduction of clays, clay-shales, &c., for the manufacture of brick, tiles, fire-brick, &c., which are pressed into form in a practically-dry state, or in the condition in which the clays, &c., are found in the mines or banks, that the particles be reduced to the smallest possible size and that a uniformity of particles be produced, and at the same time the different qualities of clay, clay-shale, &c., be thoroughly and homogeneously intermingled or mixed. It is desirable, also, in the reduction of feldspathic or granitic rocks in a dry state for uses in the various arts to which they may be applied, that the particles be of a uniform size or of a size specially adapted for the uses to which it is to be employed, as in the pulverized stone used in bituminous compounds for concrete pavements, &c. It is also desirable in the reduction of quartz and metal-bearing rocks, especially where the dry processes are used in

recovering precious metals, that the quartz or rock be reduced to the finest and most uniform powdered condition, so that the metals will be exposed to the action of the quicksilver used in recovering precious metals.

In order to carry out my invention to procure the desired results above mentioned, I subject the materials to be reduced or pulverized, of whatever kind or character, to the action of the mechanism above referred to.

The material is fed into the top of the machine, as described in the application above referred to, and has a natural tendency downward toward the bottom of the machine, caused by the force of gravity. The force of gravity is, however, partially overcome and the passage of the material through the machine retarded by the rapid rotation of the armed cylinders, which imparts to the material a violent rotary motion. The two armed cylinders revolving in the same direction divide the material as it enters the machine into two parts and carry the same in two currents through the machine. These currents, owing to the contracted form of the external shell in the center of the machine, are caused to come into violent contact or collision with each other, caused by the centrifugal force of the armed cylinders. A counter or centripetal action is also caused by the circular-formed shell, and also by the collision of the currents, and thus the materials are to a certain degree held in space while being acted upon, the cohesion of the particles of the material is destroyed and a fine powder or complete disintegration of all the particles is the result.

Having thus described my invention, what I claim, and desire to secure by Letters Patent, is—

The process herein described of reducing clay, clay-shale, and granitic or other rock or quartz to a powder, the same consisting in causing the said material to pass through a mechanism by the action of gravity, and submitting said material to the violent action of rapid-rotating armed cylinders, and disintegrating-currents, as set forth.

J. C. ANDERSON.
